US00D828619S

(12) **United States Design Patent** (10) Patent No.: **US D828,619 S**
Khubani et al. (45) Date of Patent: ** *Sep. 11, 2018

(54) **LIGHT PROJECTOR**

- (71) Applicant: **Telebrands Corp.**, Fairfield, NJ (US)
(72) Inventors: **Ajit Khubani**, Saddle River, NJ (US);
Yun Pan, Shenzhen (CN)
(73) Assignee: **Telebrands Corp.**, Fairfield, NJ (US)
(*) Notice: This patent is subject to a terminal disclaimer.
(**) Term: **15 Years**
(21) Appl. No.: **29/559,106**
(22) Filed: **Mar. 24, 2016**

Related U.S. Application Data

- (63) Continuation of application No. 29/555,447, filed on Feb. 22, 2016, now Pat. No. Des. 778,478, which is a continuation-in-part of application No. 29/526,591, filed on May 11, 2015, now Pat. No. Des. 766,483, and a continuation-in-part of application No. 29/544,568, filed on Nov. 4, 2015, now Pat. No. Des. 766,484.
